UNITED STATES PATENT OFFICE.

GEORGE SCHAEFER, OF CHICAGO, ILLINOIS.

AWNINg-FASTENER.

SPECIFICATION forming part of Letters Patent No. 783,318, dated February 21, 1905.

Application filed August 15, 1904. Serial No. 220,752.

To all whom it may concern:

Be it known that I, GEORGE SCHAEFER, a citizen of the United States of America, and a resident of Chicago, county of Cook, and 5 State of Illinois, have invented certain new and useful Improvements in Awning-Fasteners, of which the following is a specification.

My invention relates to awning-fasteners, and has for its object the construction of a 10 device by means of which awnings may be quickly and easily set up and taken down.

In carrying out my invention I provide a device which may be permanently secured to the outside of the building and which may be 15 opened and closed. I also provide a rigid bar in one edge of the awning, which bar is held by the device secure to the building.

In the accompanying drawings, Figure 1 is a perspective view of an awning supported on 20 a wall by the devices of my invention. Fig. 2 is a front elevation of the holder or fastener in its closed position with the bar shown in dotted lines. Fig. 3 is a side elevation of the holder. Fig. 4 is similar to Fig. 2, except that 25 the holder is in its open position; and Fig. 5 is a perspective view of the holder in its closed position.

The lower jaw or bracket A of the holder is provided with wings A', by which it is secured to the building, and also with a lip A², which furnishes a half-round support for the bar B. This bar is sewed or otherwise secured to the upper edge of the awning C. The 30 upper jaw D has a lip D' and is the complement of the lower jaw. The upper jaw is also provided with a projection D², which passes down through an opening in the lower jaw and by means of which the two jaws are held in proper relationship to each other. In the 35 projection D² is a hole through which is inserted an ordinary split pin E. This split pin or key serves to hold the two jaws in their closed position, so that they cannot be opened until the pin is first removed. The projection D² is made longer than necessary to hold the split pin E, and in the lower end is a permanent pin F, which prevents the two jaws from being separated from each other when 40 they are opened for hanging up or removing 45 the awning.

In applying the device two or more holders are secured to a wall or other support adja-

cent to the place to be shaded by the awning. The awning having been previously provided with a suitable bar B, the said bar is placed 55 in the lower jaws, and the upper jaws are closed down upon it. The split pins are then pushed into place. In removing the awning it is simply necessary to remove the pins E and lift the awning from its place. 60

It will be observed that the holder may and is intended to be a permanent fixture. This avoids the damage to buildings that comes from frequently putting in and taking out screws. It will also be observed that when 65 the device is once secured to the building, as on the casing of a window, it may be opened and closed by the person who is putting up or taking down the awning without it being necessary for that person to climb out of the 70 window.

What I claim is—

1. The combination with an awning, of a bracket adapted to support said awning, and a jaw coöperating with said bracket to hold 75 said awning and provided with a projection extending through said bracket to a point within said awning.

2. The combination with an awning, of a bracket adapted to support said awning, a jaw 80 coöperating with said bracket to grasp said awning and provided with a projection extending through said bracket, and a pin adapted to be inserted in said projection so as to secure said jaw to said bracket. 85

3. The combination with an awning and a rod secured in one edge thereof, of a bracket arranged to receive and hold said rod, and a jaw adapted to engage said rod so as to hold it to said bracket and provided with a projection extending through said bracket to a point within said awning. 90

4. The combination with an awning, of a clamping device therefor consisting of a stationary and a movable part, said movable part 95 being provided with a projection extending through the movable part to a point within said awning, substantially as described.

Signed at Chicago, Illinois, this 13th day of August, 1904.

GEORGE SCHAEFER.
